UNITED STATES PATENT OFFICE.

ALBERT SEPTIMUS HODGSON, OF FARNBOROUGH, ENGLAND.

CARBURETOR.

Application filed November 16, 1925, Serial No. 69,484, and in Great Britain May 21, 1924.

This invention relates to carburetors for internal combustion engines, and the object is to provide an improved construction of carburetor in which the interior of the 5 throttle chamber is divided so as to form an expansion chamber into which the fuel is admitted, and a diffuser chamber into which the fuel then passes and where it is mixed with auxiliary air before passing out 10 through aspirating ports; in which the said supply of auxiliary air is diminished as the main supply past the throttle is increased; in which the fuel is led to the expansion 15 chamber through a depression chamber having a controllable opening to the atmosphere; in which the said controllable opening may be automatically controlled so that the proportion of fuel to air may be varied automatically and maintained constant for various 20 speeds and extent of throttle opening; in which eddies and turbulences in the air stream through the carburetor may be eliminated; in which an auxiliary supply 25 of rich and highly atomized mixture may be supplied to the engine when it is desired to start from cold; and in which the connection 30 between the carburetor casing and the fuel supply chamber shall permit of a vertical, horizontal, or inclined disposition of the 35 said casing.

The invention is illustrated in the accompanying drawings, in which:

Figure 1 is a vertical sectional view mainly on the line I—I of Fig. 2.

Fig. 2 is a sectional view on the line II, 35 II of Fig. 1.

Figs. 2^A and 2^B are detail views of an automatic control device.

Figs. 3 and 4 are, respectively, a side 40 elevation and a plan view but are drawn to a smaller scale.

Figs. 5 to 7 show the general arrangement of what is substantially the arrangement illustrated in Figs. 1, 3 and 4 but with the carburetor casing turned, relatively to the float chamber, through 90 degrees from the position shown in the latter figures.

Fig. 5 is a plan view in section on the line V, V of Fig. 7.

Fig. 6 is a view corresponding to Fig. 5, but with one half of the carburetor casing, and the float chamber in plan.

Fig. 7 is a section on the line VII, VII of Fig. 5, and

Fig. 8 is a section on the line VIII, VIII of Fig. 7.

A is the carburetor casing near the forward end of which a bulbous choke core a^1 is carried by rib a^2 , the interior of the casing in proximity to the core being preferably curvilinear so as to follow the contour of the choke core periphery and so provide a converging annular passage-way leading to the engine induction pipe connection a^{10} . The core a^1 is bored concentrically, and carries a fixed hollow core a^3 the bore a^{14} of which communicates with a passage-way a^4 , the latter, on the side of the main casing opening into a depression chamber B formed at the junction between the circular facing a^5 formed on the flange a^{11} at the side of the main casing A and a facing a^6 formed on the flange a^2 of the float chamber C in which the float c is located; the depression chamber B in turn communicates through a nozzle b^1 , a passage-way b^2 , fuel jet D and passage-way b^3 (see Fig. 1) with the float chamber supplied with fuel through a conduit controlled by a float valve. Branching off from the passage-way b^2 at a point between the fuel jet D and the depression chamber B are two passage-ways e^1 and f^1 leading to devices to be described later.

The core a^3 is provided with a flange a^{12} between which and the plane rear face of the choke core is gripped an internal flange of a fixed hollow cylindrical guide a^6 concentrically arranged within the bore of the main carburetor casing. At the rear end of the carburetor casing (the lowermost end in the vertical arrangement) is a fixed centrally located hollow boss a^7 carried by webs or ribs from the main casing.

A control rod g^1 which carries the throttle K, K', has its rear end turned so as to be a sliding fit in the bore of a sleeve a^8 carried by the hollow boss a^7 carried from the ring a^{10} by the rib a^9 , the lower end of the sleeve a^8 being turned to fit the bore of the boss a^7 and having a collar which bears on the said boss a^7 , the sleeve and boss being cut away at a point opposite the rib a^9 to accommodate the actuating lever e^2 ; this rod g^1 is adapted to be moved axially in any suitable manner, preferably by a ball-headed lever g^2 engaging with a slot in the rear end of the rod; the said lever being fixed to a transverse shaft G journaled in suitable bearings carried by the ring a^{10} fixed to the casing A, the said shaft also carrying an actuating lever g^3 adapted to be operated by the driver in any

convenient manner; angular movement imparted to the shaft G imparts axial movement to the control rod and throttle. The sleeve a^8 , carried by the hollow boss a^7 , is 5 threaded and carries a fixed tubular member H which will be termed the fixed tapered member, the rear exterior configuration h^1 of which is conical. To the interior of the main casing, at a point, say, a little in 10 rear of the centre of its length is fitted a fixed ring a^{10} the interior surface of which is formed by reversely set cones; this ring which provides a venturi-like constriction of the bore of the main casing will be 15 termed the Venturi member.

The throttle takes the form of a casing K, K', having an inner part K', connected to the outer part K, and being attached by the screw k^3 to, and moving axially with 20 the control rod g^1 ; at its forward end k^2 the part K is of cylindrical configuration, its bore sliding on and being guided and supported by the exterior of the fixed cylindrical guide a^6 . The rear end k^2 of the 25 part K is of conical configuration; and cooperates with the valve seat formed by the constricted part a^{10} of the bore of the Venturi member, closing the said bore when the throttle is in its extreme rearward position, (see Fig. 1). Internally the said coned part k^2 of the throttle acting in cooperation with the coned part h^1 of the fixed taper member H, serves, when axial movement is imparted to the throttle, to control 30 the admission of air to the interior of the throttle through the open rear end thereof. A spiral spring S is fitted in the throttle which tends to move the latter rearwardly.

Through the throttle ports k^4 and k^5 are 35 formed, the latter k^5 , at that part of the throttle which acts as a valve for the venturi constriction a^{10} , and the former k^4 , in the part K'.

Fuel from the duct a^{14} in the choke core, 40 enters the space q within the sleeve a^6 and the throttle and passes through the ports k^4 into the part Q which will be termed the diffuser chamber. When the throttle is 45 partly open the movement of the air drawn, by the action of the engine suction, through the open rear end of the main casing past the venturi-like constriction, causes an aspirating action on the throttle ports k^5 ; this induces the flow of fuel through the 50 depression chamber B, passage-way a^4 , chamber Q' and ports k^4 into the diffuser chamber Q, which under normal running conditions has been previously mixed with air, as hereinafter described; the aspirating action also induces the flow of air into the 55 diffuser chamber through the end of the throttle sleeve.

The axial movement of the throttle by 60 varying the venturi-like opening controls the admission of main air past the throttle

and therefore the degree of the aspirating action on the throttle ports k^5 and the said axial movement also simultaneously controls by co-operation of the coned end of the throttle with the tapered part h^1 of the fixed member H, the admission of air to the diffuser chamber Q.

Thorough atomization and uniform admixture of air and fuel is ensured and the correct ratio of air to fuel under running conditions is thus maintained.

The fuel is led to the float chamber through a fuel supply pipe c^3 , the threaded end c^4 of which makes joint with the sleeve c^5 having a partition c^6 round which a gauze c^7 filter plate c^8 is carried, its lower edges making joint with the bottom of the fuel chamber; the upper end of the sleeve c^5 being closed by the plate c^{15} in which is formed the needle valve seat c^9 controlled by the needle valve c^{10} . Fuel entering by c^3 passes through the ports c^{10} , thence through the gauze c^7 into the chamber c^{11} , formed by the partition plate c^{12} which abuts the plate c^{15} and the packing washer c^{17} , from which chamber it passes through ports c^{12} and the seat c^8 into the fuel chamber, to a height determined by the position of the float c ; the float operating the needle valve by engaging the bulbous ends of arms c^{13} pivoted at c^{20} , the other ends of which arms engage the sleeves c^{14} fixed to the fuel valve. The cover C' of the float chamber is held in closed position by the pivoted spring c^{15}' as shown in Fig. 4.

The fuel from the float chamber after passing through the nozzle D, passes up the passage-way b^2 to the depression chamber B, and can also pass through the respective branch passage-ways e^1 and f^1 to a priming device E, and to a fuel-ratio correcting device F. Fuel is admitted to the device F to fill up the tube or passageway f^1 for a purpose later set forth. The priming device comprises a tube E' fitting in a vertical bore formed in part of the float casing C located between the float chamber and the carburetor, the lower end e^2 of the tube is screw-threaded and fits the lower screw-threaded end of the bore so that the passage-way e^1 communicates with a calibrated opening e^3 formed at the lower end of the tube.

The tube E' is provided with a port e^{10} which is preferably tapered circumferentially as shown in Fig. 2, which port aligns with the port e^9 in the casing C; the port e^9 communicates (see Fig. 5) with an annular recess e^{14} formed in the facing of the main casing A; and the said recess e^{14} communicates by a passage-way e^{15} leading to a passage-way e^{16} formed in the centre of the core a^3 , said passage-way communicating with the chamber Q' through a calibrated opening e^{17} .

Within the tube E' is fitted an inner tube e⁵, the upper end of which is open to the atmosphere, and the lower end e¹⁸ of which is smaller in diameter than the bore of the 5 tube E', and in the lower end of the tube e¹⁸ a calibrated opening e¹⁹ is provided; the larger diameter of the tube e⁵ is provided with a longitudinal groove e²⁰ which aligns with the port e¹⁰, so that the annular space 10 between the two tubes is put into communication with the port e⁹, and therefore by the described connections with the central opening e¹⁶ in the core a³.

The tube e⁵ fits the tube e' so as to be rotatable therein and is moved angularly to control the extent of port opening from the groove e²⁰ to the port e¹⁰, and the tube e⁵ is fixed in the desired angular position by a 15 locating plate e²¹ engaging with serrations 20 in the head of the tube e⁵ and secured by the bolt e²² (see Figs. 2 and 6).

The action of the priming device which may also be used for slowing running is as follows:—

25 When the main carburetor is not in operation and the throttle is closed, the fuel from the jet D passing through the passage-way e¹ enters by the opening e³ into the interior of the tube E' rising therein to a level corresponding with that of the nozzle b¹ in the depression chamber B (see Fig. 1) and therefore partly submerging the tube e⁵. Assuming now that it is desired to start the 30 engine, the suction above the throttle is high with the throttle closed and the suction effect acting through the passage-ways e¹⁶, e¹⁵, the annular recess e¹⁴, the port e⁹ in the casing C, and the port e¹⁰ in the tube E', draws, by suction action, the fuel from the tube E', 35 into the carburetor casing through the passage-way e¹⁶ thus providing a very rich mixture passing to the engine and this fuel supply is sufficient to start the engine. The tube E' having been drained, the action of slow 40 running is as follows:—

Air passes down the tube e⁵ and mixing with fuel entering through the jet e³ passes up the annular space between the tubes E' and e⁵ and the groove e²⁰, and so to the 45 engine through the ports e¹⁰, e⁹, annular groove e¹⁴, passage-way e¹⁵, and central passage-way e¹⁶, the mixture being thoroughly atomized and usually of the correct proportion.

50 Should, however, the mixture be too rich for slow running, the tube e⁵ is moved to a small extent angularly so that the groove e²⁰ is comparatively sealed off from the ports e¹⁰ and e⁹; the depression in the annular space between the tubes E' and e⁵ is therefore reduced and less fuel is supplied to the engine. The mixture strength can therefore be adjusted for slow running conditions by the angular adjustment of the tube e⁵. 55 The opening e¹⁹ at the bottom of the tube

e⁵ is adapted to form an air nozzle so that the air enters the tube E' with considerable velocity.

When the device is used for slow running, the fuel mixture passes upwardly through the opening e¹⁶, and air passes through the opening e¹⁷. The air which passes through the opening e¹⁷ is supplied thereto through the annular opening between the parts h² and h¹, passing thence through the ports h⁴ 75 and passage-way a¹⁴. When however the throttle is opened for normal running fuel from the depression chamber B is drawn through the passage-way a⁴ into the interior 80 of the throttle, and this puts the slow running device out of action since the main jet stream now draws air downwardly through the opening e¹⁷ because of the greater suction in the venturi than at port e¹⁶.

An adjustable throttle stop, (see Figs. 3 85 and 6) is fitted to regulate the idling speed of the engine, this may consist of a lug j¹ on the boss J which engages with the adjustable screw j².

Referring now to the fuel-ratio correcting 90 device F;—the lower end of the tube F' is screw threaded at f² and screws into a corresponding tapped portion of a suitable bore in the casing C, forming a vertical extension of the passage-way f¹; at the lower 95 end of the tube F' a calibrated opening f³ being formed. The bore in the casing C in which the tube F' fits is enlarged so as to form an enclosed annular space f⁶ round the 100 outside of the tube F', and this space communicates through a port and passage-way f⁵ with the depression chamber B (see Fig. 5); the annular recess f⁶ also communicates through a port f⁷ with the interior of a plug f⁸, rotatable in a suitable bore in the 105 casing C about a horizontal axis by means of a lever f⁹ actuated by a Bowden wire device f¹³ connected to a casing f¹⁴ (see Figs. 3 to 6). The plug may be screw threaded and fit a screw-threaded bore or it may be 110 plain and fit a plain bore. A retaining screw f¹⁰ is employed to engage a groove in the plug.

The bore of the plug f⁸ is provided with a lateral port f¹¹, which by the operation of 115 the lever f⁹, may be brought more or less into alignment with the air port f¹² in the casing C, the degree of port opening being dependent upon the angular position of the plug f⁸, in this way the quantity of air entering the annular space f⁶ and from the latter through the port f⁵ to the depression chamber B may be controlled.

The action of the carburetor is as follows:—

Assuming the throttle K, K' to be slightly raised from its seat a¹⁰ so as to afford a narrow venturi-like constriction for the air drawn through the casing A by the engine suction, the depression at the ports h⁶ will 130

- be considerable due to the velocity of the vehicle is climbing a steep hill, and the air past these ports, but owing to the fact that when the throttle is lifted but slightly the coned portion h^2 is comparatively clear of the coned part h^1 of the tapered member H, there is a comparatively free entry of air into the diffuser chamber Q formed in the interior of the lower part of the throttle. The depression in the chamber Q is thus maintained at a suitable value and is transmitted through the ports h^4 to the upper part or expansion chamber Q' formed in the interior of the throttle. This depression is thence transmitted through the bore of the plug a^3 and passage-way a^4 to the depression chamber B, and as the depression chamber is supplied with a regulable amount of air through the port f^5 , the depression in the chamber B will be of lower value than that existing in the diffuser chamber Q. The depression in the chamber B communicates through the jet b^1 and passage-way b^2 with the nozzle D, thus causing a flow of fuel to be drawn through the expansion chamber Q' into the diffuser chamber Q where, before passing out through the ports h^5 into the main air stream, it is thoroughly mixed with air entering between h^2 and h^1 .
- It will further be noted that fuel passing through the nozzle b^1 is diffused with air entering the depression chamber through the port f^5 and as the latter air is controlled by the correcting device, the correct mixture for a predetermined position of the throttle can be determined, and when this is done I find that for any other position of the throttle the apparatus will maintain this correct proportion.
- If now the throttle be raised to a higher position, say half its range, the depression acting at the ports h^5 will be reduced in consequence of the reduction of the constriction on the air stream and the reduced velocity of the latter, and for this reason the depression in the diffuser chamber Q would also tend to be reduced were it not for the fact that as the throttle rises the joint action of the part h^2 and the part h^1 results in the closing of the end opening to the diffuser chamber Q, the effect of which increases the depression in the diffuser chamber to the extent necessary for the correct flow of fuel to the increased air flow.
- When the throttle is raised to the full-open position the part h^2 practically closes the end opening to the diffuser chamber, the depression then being a maximum. It follows, therefore, that for all normal conditions of engine running the air-fuel ratio is maintained in correct proportion.

In order to meet all the demands required in internal combustion engines under various conditions, for instance when the motor

speed is reduced by reason of excess load, when there will be a reduction of air velocity through the carburetor with a consequent reduction of depression with fixed throttle; the flow of liquid under variable pressure does not vary in the same way as the flow of air under variable pressure, and the mixture in such cases would tend to become weak and the engine rapidly loses power; this defect is overcome by the operation, either automatically or by hand, of the mixture correcting device F'.

The action of this device is as follows:

When the carburetor is in a slow running position the fuel level in the float chamber rises to a height just below that of the nozzle b^1 in the depression chamber B, the main jet D is therefore submerged, and the fuel rises in the passage-way f^1 sealing the port f^3 in the tube F'. When the throttle is more fully opened, the depression formed in the chamber B is such that the fuel level in the passage-way f^1 and the passage-ways b^2 is lowered to the level of the orifice of the jet D; the passage-way f^1 is now clear of fuel, and air enters through the calibrated orifice f^3 and is diffused with the fuel passing from the jet D with the resulting reduction of depression at D.

As a consequence, the amount of air passing through the tube f^1 is sufficient to ensure the correct amount of fuel passing when the engine is running at full throttle with normal revolutions and load. Had it not been for this correcting device the amount of fuel would be too large for engine requirements of normal revolutions and load.

The correcting device may be further controlled through the plug f^8 by hand or automatically through a thermostat.

The operation of the plug f^8 by the lever f^9 actuated by a Bowden wire or any other suitable transmission means under the control of the driver, may be made to control the admission of air to the annular space f^6 and thus through the port and passage-way f^5 to the depression chamber B. For instance, the port f^{12} may be closed altogether, in which case the mixture would be very rich; or it may be opened to such an extent as to render the depression in the chamber B negligible, and this may be done when it is desired to apply an air-brake to the engine of a motor vehicle descending hills, and thereby effecting economy in fuel consumption, under such conditions.

As is well known an internal combustion engine requires a richer mixture until it becomes hot enough to run efficiently, after which the mixture of fuel and air can be appreciably weakened; when therefore the correcting device is not operated by hand,

automatic means may be employed, a suitable form of which is shown in Figs. 2^A and 2^B, the construction of which is as follows:—

The plug f^8 and its lever f^9 are removed, 5 and are replaced by a threaded sleeve m^1 which closes the port f^{12} , and the bore of which communicates with the port f^7 ; the bore of the sleeve m^1 is connected by a flexible tube m^2 to the threaded end m^3 of an 10 air-control valve casing m^4 , in which is formed a valve seating m^5 ; air admission through this seat being controlled by a valve p^1 actuated by any suitable form of thermostat control device. In the drawings the 15 valve p^1 is actuated by a thermostat P which comprises an extensible tube p^2 filled with air or other suitable medium which is imprisoned therein; one end of the tube p^2 is connected to the thermostat casing by the 20 bolt p^3 , and the free end of the tube is connected by a rod p^4 to the valve p^1 . The casing m^4 can be initially adjusted relatively 25 to the valve p^1 by screwing it on or off the screwed end of m^3 and it is fixed in position by means of the nut m^6 .

The thermostat is located in respect to the engine, say in the crank casing, so that the temperature of the fluid in the thermostat casing P varies, with as little time lag as 30 possible, with the engine temperature or the temperature of the cooling water.

The action of the automatic device is as follows:—

When the engine is cold the valve p^1 is 35 closed or nearly closed and little or no air is supplied through the port f^5 to the depression chamber B ; the mixture supplied to the engine is therefore rich enough to ensure easy starting.

As the engine temperature rises, heat is communicated to the extensible tube p^2 , whereupon the tube p^2 extends and opens the valve admitting air through the valve seating m^5 , flexible tube m^2 , port f^7 and port f^5 45 to the depression chamber B , the effect of which is to gradually weaken the mixture until when the engine is sufficiently hot it is operated efficiently by a suitable mixture.

The setting of the valve p^1 is such as to 50 supply the right amount of air to the depression chamber B to ensure the correct air-petrol ratio, and this adds to the economy and efficient running of the engine.

The maximum opening of the valve p^1 is 55 limited in any convenient manner, say by an adjustable screwed plug p^6 engaging with the collar p^7 , so that should the engine become unduly hot the mixture strength is not abnormally affected.

While I refer to the substitution of the sleeve m^1 for the plug f^8 , obviously the plug and the sleeve may be located in different seatings arranged to communicate with the annular space f^6 .

The arrangement described is found to 65 give excellent results, but the details of construction may of course be modified according to the size and duty of the carburetor.

Having now fully described my invention, I declare that what I claim and desire to 70 secure by Letters Patent is:—

1. In a carburetor, in combination, a main casing having a bore one end of which forms the carburetor outlet, and the other end of which opens to the atmosphere, a constriction in said bore, a hollow throttle axially movable in said bore and controlling the air flow through the annulus between the throttle and the said constriction, a fixed main fuel conduit connected to the fuel supply, a 75 fixed cylindrical sleeve at the forward end of the throttle and into the interior of which the fixed conduit opens and with which the forward end of the throttle makes a sliding joint, aspirating ports in the wall of the throttle the extent of opening of which is regulated by axial movement of the throttle, a perforated partition dividing the interior of the throttle into two chambers, one an 80 expansion chamber into which the main fuel conduit leads and the other a diffuser chamber in the walls of which the aspirating ports are formed and to the rear end of which air is admitted by the controllable means, the said fuel passing to the said diffuser chamber through the expansion chamber, means for controlling the admission of air through the rear end of the throttle which reduce the area for the admission of 85 said air as the throttle is opened, and means for axially moving the throttle.

2. In a carburetor, in combination, a main casing having a bore one end of which forms the carburetor outlet, and the other end of which opens to the atmosphere, a constriction in said bore, a hollow throttle axially movable in said bore and controlling the air flow through the annulus between the throttle and the said constriction, a fixed main fuel conduit connected to the fuel supply, a 100 fixed cylindrical sleeve at the forward end of the throttle and into the interior of which the fixed conduit opens and with which the forward end of the throttle makes a sliding joint, aspirating ports in the wall of the throttle the extent of opening of which is regulated by axial movement of the throttle, a fixed bulbous choke core located in the 105 main bore of the carburetor casing, in which the main fuel conduit is located and by which the cylindrical sleeve is carried, and means for reducing the admission of air through the rear end of the throttle as said throttle opens, substantially as described.

3. In a carburetor, in combination, a main casing having a bore one end of which forms the carburetor outlet, and the other end of which opens to the atmosphere, a constric-

- tion in said bore, a hollow throttle axially movable in said bore and controlling the air flow through the annulus between the throttle and the said constriction, a fixed main fuel conduit connected to the fuel supply, a fixed cylindrical sleeve at the forward end of the throttle and into the interior of which the fixed conduit opens and with which the forward end of the throttle makes a sliding joint, aspirating ports in the wall of the throttle the extent of opening of which is regulated by axial movement of the throttle, starting means comprising an auxiliary conduit connected with the fuel supply and discharging into the bore of the main casting at the outlet thereof, a connection from said auxiliary conduit to the atmosphere, and a calibrated opening connecting the said auxiliary conduit with the main fuel conduit, whereby when the throttle valve is open for normal running the starting means is put out of service by the passage of air through said auxiliary conduit and calibrated opening, means for controlling the admission of air through the rear end of the throttle which reduce the area for the admission of said air as the throttle is opened, and means for axially moving the throttle.
- 30 4. In a carburetor, in combination, a main casing having a bore one end of which forms the carburetor outlet, and the other end of which opens to the atmosphere, a constriction in said bore, a hollow throttle axially movable in said bore and controlling the air flow through the annulus between the throttle and the said constriction, a fixed main fuel conduit connected to the fuel supply, a fixed cylindrical sleeve at the forward end of the throttle and into the interior of which the fixed conduit opens and with which the forward end of the throttle makes a sliding joint, aspirating ports in the wall of the throttle the extent of opening of which is regulated by axial movement of the throttle, means for controlling the supply of air to the rear end of the throttle comprising a turned in lower end of the throttle and a fixed coned part cooperating therewith, the forward end of said coned part being of larger diameter than the rear end and means for operating the throttle.
- 35 5. In a carburetor, in combination, a main casing having a bore one end of which forms the carburetor outlet, an atmosphere port, a fixed main fuel conduit connected to a fuel supply, a depression chamber connected to the main fuel conduit, a fuel nozzle in the said chamber, a submerged jet connected to the fuel supply, a conduit between said jet and said nozzle, a regulable opening for the admission of air to said chamber, a vertical tube the upper end of which is open to the atmosphere, a calibrated opening in the lower end of said tube, and a conduit connecting the said calibrated opening to the conduit connecting the submerged jet to the nozzle in the depression chamber.
- 40 6. In a carburetor in combination a main casing having a bore one end of which forms a carburetor outlet, an atmosphere port, a fixed main fuel conduit connected to a fuel supply, a depression chamber connected to the main fuel conduit, a fuel nozzle in the said chamber, a submerged jet connected to the fuel supply, a conduit between said jet and said nozzle, a regulable opening for the admission of air to said chamber, a vertical tube the upper end of which is open to the atmosphere, a calibrated opening in the lower end of said tube, and a conduit connecting the said calibrated opening to the conduit connecting the submerged jet to the nozzle in the depression chamber.
- 45 7. In a carburetor, in combination, a main casing, an axially movable throttle, a perforated diaphragm in the throttle dividing it into an expansion chamber and a diffuser chamber, a depression chamber connected to the expansion chamber, a nozzle in the depression chamber connected to the fuel supply, a regulable air inlet to the depression chamber, aspirating ports in the diffuser chamber, the extent of opening of which is controlled by movement of the throttle, means for controlling the supply of air to the diffuser chamber in accordance with the extent of opening of the throttle, and means for moving the throttle.
- 50 8. In witness whereof I have hereunto set my hand.
- 55 ALBERT S. HODGSON.
